UNITED STATES PATENT OFFICE.

FRANK H. FRISSELL, OF MIDDLETOWN, CONNECTICUT, ASSIGNOR TO RUSSELL MFG. CO.,
OF MIDDLETOWN, CONNECTICUT, A CORPORATION.

MACHINE-GUN FEED-BELT.

1,258,553.

Specification of Letters Patent.

Patented Mar. 5, 1918.

Application filed December 28, 1917. Serial No. 209,208.

To all whom it may concern:

Be it known that I, FRANK H. FRISSELL, a citizen of the United States, residing at Middletown, in the county of Middlesex and State of Connecticut, have invented a new and useful Improvement in Machine-Gun Feed-Belts; and I do hereby declare the following, when taken in connection with the accompanying drawings and the characters of reference marked thereon, to be a full, clear, and exact description of the same, and which said drawings constitute part of this application, and represent, in—

Figure 1 a broken plan view of a machine-gun feed-belt constructed in accordance with my invention and in part filled with cartridges.

Fig. 2 an edge view thereof looking at the head ends of the cartridges and the outer edge of the belt.

Fig. 3 an enlarged sectional view on the line 3—3 of Fig. 1.

Fig. 4 a view in transverse section of one of the modified forms which the belt may assume.

My invention relates to an improved machine-gun feed-belt, the object being to produce a superior belt provided with special means for the frictional retention of the cartridges therein, whereby they are prevented from falling out of the belt when the same is being handled, or after the same has been applied to a gun, the belt being particularly adapted for use in connection with machine-guns carried by air-planes which when in use, are subject to excessive vibration, tending to dislodge the cartridges.

With these ends in view, my invention consists in a machine-gun feed-belt having one or more cartridge-retaining friction strands superimposed upon the inner faces of its cartridge-receiving pockets so as to produce raised points of contact for the cartridges.

My invention further consists in a machine-gun feed-belt having certain details of construction as will be hereinafter described and pointed out in the claims.

In carrying out my invention, as shown in Figs. 1 to 3 inclusive, I superimpose oppositely located cartridge-retaining strands 4 upon the inner faces of the cartridge-receiving pockets 5 of the belt which may be of any approved construction, the said strands being parallel with the length thereof. As shown, the strands 4 are secured in place by loops 6 thrown around them at intervals during the weaving of the belt, but I do not limit myself to any particular mode of securing the strands in place. By preference the strands will be made of thread impregnated with asphalt or some other adhesive substance. If preferred, however, I may employ wire strands which, on account of being superimposed upon the inner faces of the pockets, will have the effect of frictionally retaining the cartridges 7 in place. In the modified form of my improved belt shown in Fig. 4, I employ two pairs of oppositely located strands 8, and hold myself free to employ one or more strands as found expedient.

I claim:—

1. A machine-gun feed-belt having one or more cartridge-retaining strands superimposed upon the inner faces of its cartridge-receiving pockets for frictionally retaining the cartridges therein. 75

2. A woven machine-gun feed-belt having one or more cartridge-retaining strands superimposed upon the inner faces of its cartridge-receiving pockets and held in place by loops produced in the weaving of the belt. 80

3. A machine-gun feed-belt having one or more adhesive cartridge-retaining strands superimposed upon the inner faces of its cartridge-receiving pockets for frictionally retaining the cartridges therein. 85

In testimony whereof, I have signed this specification in the presence of two subscribing witnesses.

FRANK H. FRISSELL.

Witnesses:

H. A. POPP,
A. H. STRICKLAND.
